UNITED STATES PATENT OFFICE.

OLIVER BROTHERS, OF NAUGATUCK, CONNECTICUT, ASSIGNOR TO
HIMSELF AND JOSEPH WHITE, OF SAME PLACE.

IMPROVEMENT IN SPINNING-JACKS.

Specification forming part of Letters Patent No. 87,138, dated February 23, 1869.

To all whom it may concern:

Be it known that I, OLIVER BROTHERS, of Naugatuck, in the county of New Haven and State of Connecticut, have invented a new and Improved Automatic Bobbin-Builder for Spinning-Jacks; and I do hereby declare that the following is a full, clear, and exact description thereof, which will enable others skilled in the art to make and use the same, reference being had to the accompanying drawings, forming a part of this specification.

Figure 1, Sheet I, represents a side elevation of my improved bobbin-builder. Fig. 2, Sheet I, is a vertical longitudinal section of the same, taken on the plane of the line $x x$, Fig. 1. Fig. 3, Sheet II, is a plan or top view of the same. Fig. 4, Sheet II, is a detail vertical section of the same, taken on the plane of the line $y y$, Fig. 3. Fig. 5, Sheet II, is a detail perspective view of the cam which operates the faller of the machine up and down.

Similar letters of reference indicate corresponding parts.

This invention relates to a new machine for automatically winding the yarn around the bobbins of a wool-spinning machine, its object being to do away with the necessity of imparting oscillating motion by hand to the faller or thread guide.

The invention consists in such an arrangement of all parts that a bobbin of suitable size can be built of suitable shape altogether automatically.

A in the drawing represents a slotted horizontal plate, which is provided with projecting arms $a a$, that are secured to the reciprocating carriage of a wool-spinning jack. From the plate A projects upward an ear or post, b , which forms a bearing for a horizontal screw-shaft, B. On the outer end of this shaft is mounted a ratchet-wheel, C, to the center of which a lever, D, carrying a pawl, c, is pivoted.

E represents a rod, which is held in bearings $d d$, that are attached to the carriage or to the plate A, and which can freely slide in its bearings. It is, as in Fig. 1, pivoted at one end to the lever D, while its other end projects forward toward the stationary bobbin-frame.

Whenever the carriage moves forward the

front end of the rod E will abut against a plate or knob, e, formed on the stationary frame, and will be pushed back, so as to cause the lever D to swing. The pawl will thereby be carried forward, so as to cause the wheel C to turn, and to also turn the shaft B.

When the carriage moves back, a spring, f, or its equivalent, carries the rod E forward again into the original position, and thereby the pawl is brought back on the wheel C, so as to fall into another tooth, ready to turn the wheel a when the rod is pushed back again. Intermittent rotary motion is thus imparted to the shaft B by the reciprocating motion of the carriage.

On the shaft B is formed a screw-thread, as in Fig. 2.

The screw B is fitted through a truck or frame, F, which rests on the plate A, between or upon two flanges or rails, g g, that project from the plate, as shown. When the screw is turned by the aforesaid action of the pawl and ratchet-wheel, it serves to draw the truck F toward the ratchet-wheel.

G represents a vertical shaft. The same fits loosely through a block, h, on which V-shaped lugs or projections i i are formed, pointing downward, as shown in Fig. 2. These lugs rest with their points upon the upper edges of the frame F, and serve to suspend the shaft G from the said truck or frame F, the shaft having a shoulder, by means of which it is suspended from the block h. The lower end or part of the shaft G fits through an arm, j, that is secured to the carriage and adjustable vertically. The shaft is thereby prevented from lateral motion, but it is allowed to move up and down with the arm j.

The shaft G receives, by suitable connection with the shaft H, rotary motion.

Those edges of the truck F upon which the points i rest are partly horizontal and partly inclined, as shown—that is, that portion which is nearest to the ratchet-wheel is highest, and is horizontal, and that portion which is away from the ratchet-wheel is slanting downward from the horizontal part, as shown.

As the truck is, by the motion of the screw, drawn toward the ratchet-wheel, it moves from under the lugs i, the shaft always remaining suspended from the truck.

As long as the lugs *i* rest on the horizontal portion of the edge the shaft will always remain at an equal height; but as the inclined portion of the edge arrives under the lugs, as in Fig. 2, the shaft will gradually be lowered as the truck *F* is drawn to the ratchet-wheel.

The shaft and pinion are connected by a feather in the latter, fitting into a groove in the former, whereby the shaft is permitted to slide easily through the pinion, but cannot turn with the same.

On the lower part of the shaft *G*, above the arm *j*, is mounted a cam-disk, *I*, as shown.

J is an upright bar, fitted through arms *k l*, that project respectively from the plate *A* and arm *j*, as in Fig. 1, and is provided with a projecting step, *m*, which rests upon the upper face of the cam *I*, as shown in Fig. 1. The step is adjustable vertically on the bar *J*, for purposes hereinafter to be specified.

The slot in the lower arm *l* is longer than the width of the bar *J*, so that the bar may swing somewhat in its holders. To one side of the bar *J* is secured a spring, *L*, from one side of which two V-shaped lugs, *n n*, project through a slot in the bar *J*, as shown in Figs. 1 and 4.

From the upper end of the spring *L* projects an arm, *o*, in a horizontal direction, as shown in Figs. 1 and 3. From the upper end of the shaft *G* projects an arm, *p*, in a horizontal direction, as shown in the same figures. When the shaft is, during the forward motion of the carriage, turned in the direction of the arrow 1, Figs. 3 and 5, its arm *p* will, at every revolution, strike against the arm *o*, so as to bend the upper end of the spring *L* away from the bar *J*, and to thereby draw the lugs *n n* from the slot of the bar *J*, as shown in Fig. 4, in which figure the spring is represented as being pressed back.

M is a crank or lever projecting from the shaft *N*, with which, by means of arms *r r*, the faller or thread-guide *O* is connected, as indicated in Figs. 1 and 3. The rear end of the lever *M* is, when the spring *L* is in its undisturbed position, held between the lugs *n n*, and thereby, as the bar *J* is moving up and down, the lever is made to swing and cause the shaft *N* to oscillate and the wire *O* to be lowered or raised. When the lugs *n n* are, by the action of the arm *p*, withdrawn, as in Fig. 4, the lever will be released, and its rear end will fall down, so as to cause the guide *O* to fly up.

From the sliding truck *F* projects an arm, which carries a slotted plate, *P*. Through the slot in this plate *P* is fitted the bar *J*, and as the truck moves on the plate *A* the slotted arm will be carried along with it, causing the bar *J* to follow the shape of the slot. For this purpose the aforesaid swinging play is allowed the bar.

The operation of the apparatus is as follows: The bobbins *R R* are set upon the stationary part of the spinning-jack, and the yarn is conducted to them from the ordinary

rollers under the guide *O* and above the stripper *S*. The position of the guide *O* controls the yarn at the required height on the bobbin. At the start—that is, when an empty bobbin is to be filled—the shaft *G* is suspended from the uppermost horizontal edge of the truck, whereby, as the cam *I* is firmly keyed to the shaft, and as the bar *J* also rests on the cam, the said bar and its appendage are elevated, holding the lugs *n n* up high. The rear end of the lever *M* will thereby also be raised, and will hold the guide *O* down, so that thus, at the start, the thread is guided to the lower part of the bobbin, each backward and forward movement of the carriage will cause the truck to be drawn nearer to the ratchet-wheel, and the shaft will consequently be lowered the more the inclined portion of the truck recedes from under the lug *i*. The more it is lowered the higher will the guide *O* be held, and the higher will the thread be wound around the bobbin. Thus, by the inclined upper face of the truck *F*, the yarn is guided gradually from the lower to the upper end of the bobbin.

The shaft *G* makes almost a full revolution during each oscillation of the lever *M*. It is turned in the direction of the arrow 1 when the carriage moves forward, and in the opposite direction when it moves backward. At the start of the forward motion the step *m* rests upon the lowermost portion *s* of the cam, as in Fig. 1. The bar *J* is therefore down as low as it can be during the revolution, and the guide *O* is consequently as high as it can be during the same motion. As the cam is now turned the step *m* will pretty suddenly be raised to the highest point *t* of its edge, which is only about ninety degrees distant from the lowest points. The thread is thereby brought quickly from the uppermost to the lowermost portion of the bobbin that can be reached during the one revolution. Now the edge of the cam very gradually descends from *t* to *s* again, and allows the thread to be built up around the bobbin from below.

It will be understood that the thread is guided by the rod *O*, which has its position regulated by the lever *M*. The latter is held between the lugs *n n*, and is turned with its pivot *N* by the up-and-down motion, the same being not only caused by the gradual descent of the shaft *G* on the truck *J*, but also during each turn of the shaft during the forward motion of the carriage by the shape of the cam *I*.

When the carriage is quite forward the lever *M* is, as heretofore set forth, freed from the lugs *n*, and the guide *O* flies up, leaving the thread free to be twisted during the backward motion of the carriage.

The cam is slightly conical—*i. e.*, it is higher in the center than at some portions of the edge—as shown. The step *m* would thereby at times rest higher if it were brought nearer to the center of the cam than it would be when resting upon the outermost portion of the same. The slot through the plate *P* is straight, except at

the ends, where it is inclined toward the plate A, as shown in Fig. 3. The bar J will therefore, when it is in one of the ends of the slot, be nearer to the shaft G, and therefore higher, as its step *m* rests nearer to G on the cam, than it is when it is in the straight part of the slot. Thus, at the start, the bar J is, in the end *w* of the slot, higher on the cam. The motion of the bar caused by the cam will be less now than afterward, when the step rests on the outer part of the cam, the distance between the lowermost part *s* and the highest part *t* of the cam being in the former case less than in the latter. Consequently the taper formed on the bobbin will be less when the bar J is thus nearer to G. At the start, therefore, this taper is short, but is gradually lengthened until the bar J is in the straight part of the slot; then it remains uniform. Near the top of the bobbin the taper is again shortened as the bar J gets into the end X of the slot. In this manner the bobbin can be quite automatically built up, without requiring the tiresome and unreliable personal attendance to the guide O. The step *m* is adjustable on the bar J for the purpose of adapting the device to longer or shorter bobbins.

I claim as new and desire to secure by Letters Patent—

1. The cam I on the shaft G, in combination with the adjustable step *m*, bar J, and slotted plate P, substantially as described, for the purpose specified.

2. The rotating shaft G suspended from a movable carriage or truck, F, with a partly inclined bearing edge or face, substantially as herein shown and described.

3. The block *h*, having the lugs *i*, and sur-

rounding the shaft G, when arranged, as described, for suspending the shaft from the truck F, as specified.

4. The combination of the truck F on the bed A, the screw B, ratchet-wheel C, pawl *c*, and lever D with the sliding shaft G, all arranged and operating as described, for the purpose specified.

5. The bar J, supported by the revolving cam I, and provided with a spring, L, on which the lugs *n* for holding the lever M are formed, substantially as herein shown and described.

6. The arms *o* and *p*, projecting, respectively, from the spring L and from the shaft G, for the purpose of releasing the yarn during the backward motion of the carriage, to give it proper twist, as set forth.

7. The step *m*, when arranged adjustably on the bar J, for the purpose substantially as set forth.

8. The slotted plate P for guiding the bar J, and when secured to the sliding truck F, so as to regulate the taper of the bobbin, as set forth.

9. The lever M for operating the faller, in combination with the spring L, having the lugs *n*, as and for the purpose specified.

10. An automatic bobbin-builder for spinning-machines, consisting of the bed-plate A, screw B, carriage F, shaft G, cam I, bar J, step *m*, spring L, and lever M, all combined with each other, and made and operating substantially as herein shown and described.

OLIVER BROTHERS.
